ELECTRON DISCHARGE DEVICE OF THE
VELOCITY MODULATION TYPEGeorge C. Sziklai, Princeton, N. J., assignor to
Radio Corporation of America, a corporation
of Delaware

Application August 25, 1945, Serial No. 612,651

13 Claims. (Cl. 315—6)

1

My invention relates to electron discharge devices and associated circuits and particularly to such devices and circuits useful at ultra high frequencies and employing the principles of velocity modulation and inductive output.

In certain types of tubes referred to as velocity modulated inductive output tubes, a beam of electrons is directed along a space path toward a collector. Positioned along the path of the electrons is a means for producing a high frequency electric field to which the electrons are subjected, as a result of which the velocities of the electrons in the stream are varied. The electrons are then permitted to drift along the path so that slow electrons are overtaken by fast electrons to form groups of the electrons. At the point of grouping, electrons are subjected to a second high frequency electric field to which they deliver energy and are then collected by the collector. Normally the devices for producing the fields are cavity resonators which confine the fields and which are apertured to permit the electrons to pass through the resonators.

In this type of device the random initial velocities of the electrons released from the electron source, usually an indirectly heated cathode, may drastically affect the efficiency and output of the system, particularly where the applied voltage in the first field is of the same order or smaller than the potentials corresponding to the variations in the initial velocities of the electrons before they reach the first high frequency field. As a result the electrons are not grouped in a desirable manner along the drift space and the groups of electrons do not enter the second high frequency field in such fashion as to deliver maximum energy to this field. In effect the bunching of the electrons taking place purely due to the random initial velocities masks to some degree the bunching effected by the first resonator or accelerating electrode, or again under these conditions the second high frequency field or second cavity resonator is in the right position only for electrons of certain initial velocity range and therefore only a fraction of the electrons contribute to the output of the device.

Attempts have been made to neutralize or eliminate the electrons which are not in proper phase and which do not contribute to the output of the device. However this does not contribute to the efficiency of the device. Under these conditions the alternating voltage output compared to the D.-C. input is no better than in conventional velocity modulated devices although an

2

improvement in the sensitivity of the device might result.

It is, therefore, an object of my invention to provide an improved electron discharge device and associated circuit, particularly for use at ultra high frequencies and employing velocity modulation and inductive output.

A further object of my invention is to provide an improved device of this type employing cavity resonators.

A more specific object of my invention is to provide a device and associated circuit of the type described in which the effect of bunching in the drift space due to random initial velocities is substantially reduced, thereby improving the efficiency and sensitivity of the device.

The novel features which I believe to be characteristic of my invention are set forth with particularity in the appended claims, but the invention itself will best be understood by reference to the following description taken in connection with the accompanying drawing in which the figure is a longitudinal section of one form of electron discharge device of the amplifier type and associated circuit made according to my invention.

An evacuated envelope 10 is provided at one end with an indirectly heated cathode and gun structure 11 for supplying a beam of electrons 30 and at the other end with a collector 20. Positioned adjacent the cathode are a pair of preferably curved electrodes in the form of plates 12 and 13 between which the electrons are directed. A constant difference of potential as indicated 35 is applied between the electrodes so that electrons directed between these electrodes are subjected to a transverse electrostatic field. As a result of the action of the electrostatic field the electrons are made to travel substantially circular curved paths, such that the slower electrons are deflected to the greatest extent and vice versa. In some cases a constant magnetic field normal to the electron path (in the drawing normal to the plane of the drawing) may be used instead of the 40 deflecting plates. This magnetic field could be established, for example, by the magnet 13'. The length of the plates is several times the distance therebetween, whereby the electron stream will be deflected through a substantial angle. This angle is shown in the drawing as being about 90°.

Positioned transversely in the path of the electron stream are a pair of spaced grid members 14 and 15 for defining an ultra high frequency electric field therebetween, these grids 55 forming the wall portions of a cavity resonator

16 which may be excited by any suitable means. The grids are so positioned that the fast and slow electrons leaving the cathode at any one instant arrive at the surface of the grid 14 at substantially the same instant, the potential of the resonator 16 and grid 14 relative to the potentials of the deflecting plates 12 and 13 causing the electrons to continue to travel curved paths in the space between the plates 12 and 13 and the grid 14. The electrons are velocity modulated in passing between the grids 14 and 15 by the field set up in the resonator 16, in a manner now well known so that electrons leaving the surface of the second grid 15 have superimposed thereon the acceleration or deceleration 15 caused by the field within the resonator, the acceleration or deceleration depending upon the instantaneous potentials of the grids at the entry of the electron into this space. The electrons then proceed along a drift path parallel to the longitudinal axis of the straight portion of the tube, wherein the slow and fast electrons become grouped at the frequency of the field within the resonator 16. Inasmuch as the faster electrons cover a greater distance than the slower electrons, the grouping along a transverse section will occur along a plane inclined at an angle to the path of the electrons. In order to utilize the effective grouping a second resonator 19 provided with the grids 17 and 18 is mounted transversely and at such an angle to the path of the electrons that all electrons of each group enter the space between the grids 17 and 18 at substantially the same instant of time, thus fully utilizing all electrons regardless of initial velocity at the cathode 11. The electrons after delivering energy to the resonator 19 in a manner now well understood, are collected by collector 20. The spacing between the resonators 16 and 19 is such that the electrons attain their maximum grouping when they enter the resonator 19 so as to deliver maximum energy to the electric field in this resonator. The space between the grids 15 and 17 could be, if desired, shielded from outside influences by a conducting sleeve not shown and electrically connected to one or both of the resonators. The various required voltages are supplied by means of the voltage source 21. The output may be coupled to resonator 19 by the coaxial line and loop 22.

It will be apparent from this description that theoretically all of the electrons are made available for supplying energy to the output and the effect of initial random velocities is substantially neutralized. Thus the efficiency of the device is much improved as well as the sensitivity.

While I have indicated the preferred embodiments of my invention of which I am now aware and have also indicated only one specific application for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims.

What I claim as new is:

1. An electron discharge device comprising means for supplying a stream of electrons having random initial velocities along an electron beam path, means adjacent the electron supplying means for deflecting said electrons inversely to the random initial velocity of the electrons, means for defining a high frequency field in the

path of said electrons and extending transversely to the beam path at a point past the deflecting means, said field causing velocity modulation of said electrons whereby the electrons become grouped, and means for defining a second high frequency field in the path of said electrons and inclined at an angle to the electron path so that all the electrons of each group arrive at said second high frequency field at substantially the same instant of time.

2. An electron discharge device comprising means for supplying a stream of electrons having random initial velocities along an electron beam path, means adjacent the electron supplying means for deflecting said electrons inversely to the random initial velocity of the electrons, cavity resonator means for defining a high frequency field in the path of said electrons and extending transversely to the beam path and positioned at a point past the deflecting means, said field causing velocity modulation of said electrons whereby the electrons become grouped, and a second cavity resonator means for defining a second high frequency field in the path of said electrons and inclined at an angle to the electron path so that all the electrons of each group arrive at said second high frequency field at substantially the same instant of time.

3. An electron discharge device comprising cathode means for supplying a stream of electrons having random initial velocities along an electron beam path, means adjacent the electron supplying means for deflecting said electrons inversely to the random initial velocity of the electrons, a final electrode toward which said electrons are directed, a first cavity resonator means for defining a high frequency field in the path of said electrons and along a plane transverse to the beam path at a point past the deflecting means, whereby electrons with different random velocities and leaving the cathode means at any instant arrive at said field together, said field imposing a velocity modulation component on said electrons whereby the electrons become grouped, and a second cavity resonator means for defining a second high frequency field and positioned between said first cavity resonator means and said final electrode, said second cavity resonator means being inclined at an angle to the electron path whereby the electrons of each group all pass through said second high frequency field at substantially the same instant of time.

4. An electron discharge device comprising means for supplying a stream of electrons of random initial velocities along an electron beam path, means along said beam path for deflecting said electrons inversely to their random initial velocities, and means disposed in the path of said electrons at a point past said deflecting means and cooperating with said deflecting means for causing said electrons to travel along curved paths after said deflection, said last means including means for defining a first high frequency field through which said electrons are directed, said last means being positioned transversely of the beam path, whereby all electrons initially leaving said electron supplying means at any instant reach said field together, said field defining means velocity modulating the electrons passing therethrough whereby velocity variations are superimposed on the initial random velocities of said electrons, said electrons becoming grouped after passage through said field, and means spaced along the electron path for de-

fining a second high frequency field, said last means being inclined at an angle to the electron path whereby the fast and slow electrons of each group pass through said second field at substantially the same time.

5. An electron discharge device comprising means for supplying a stream of electrons of random initial velocities along an electron beam path, means along said beam path for deflecting said electrons inversely to their random initial velocities, and means disposed in the path of said electrons at a point past said deflecting means and cooperating with said deflecting means for causing said electrons to travel along curved paths after said deflection, said last means including means for defining a first high frequency field through which said electrons are directed, said means being positioned transversely of the beam path, whereby all electrons initially leaving said electron supplying means at any instant reach said field together, said field defining means velocity modulating the electrons passing therethrough whereby velocity variations are superimposed on the initial random velocities of said electrons, said electrons becoming grouped after passage through said field, and means spaced along the electron path for defining a second high frequency field, said last means lying along a plane inclined at an angle to the electron path whereby the fast and slow electrons of each group pass through said second field at substantially the same time, said field defining means including resonators through which the beam path extends and having grids defining said fields.

6. An electron discharge device comprising an elongated envelope curved at one end, means in the curved end of said envelope for supplying a stream of electrons of random initial velocities along a space path through said envelope, an electrode at the other end of said envelope, means along said space path for deflecting said electrons inversely to their random initial velocities, and a first resonator disposed in the path of said electrons at a point past said deflecting means and cooperating with said deflecting means for causing said electrons to travel along curved paths, the faster electrons travelling paths of greater radii, said resonator including means for defining a high frequency field through which said electrons are directed, said resonator being positioned transversely of the beam path, whereby all electrons initially leaving said electron supplying means at any instant reach said field together, said resonator velocity modulating the electrons passing therethrough whereby velocity variations are superimposed on the random initial velocities of said electrons, said electrons becoming grouped after passage through said field, and a second resonator spaced along the electron path for defining a second high frequency field, said second resonator lying along a plane inclined at an angle to the electron path whereby the fast and slow electrons of each group pass through said second field at substantially the same time.

7. An electron discharge device comprising means for supplying a stream of electrons having random initial velocities along an electron beam path, means adjacent said electron supplying means for deflecting said electrons inversely to the random initial velocities of the electrons and causing said electrons to travel along curved paths wherein the faster electrons are deflected to a smaller extent and travel longer paths in a given time than the slower electrons, and cavity

resonator means for defining a high frequency field in the path of said electrons, said last-named means being disposed in a plane transverse to the beam path at a point past said deflecting means and so oriented that all electrons leaving the electron supplying means at the same instant of time arrive at said cavity resonator means at substantially the same instant of time.

10. An electron discharge device according to claim 7, further including a second cavity resonator means for defining a second high frequency field in the path of said electrons, said second cavity resonator means being located beyond and inclined at an angle to said first resonator means so that all electrons of each group arrive at said second high frequency field at substantially the same instant of time.

8. An electron discharge device comprising means for supplying a stream of electrons having random initial velocities along an electron beam path, means adjacent said electron supplying means for deflecting said electrons inversely to the random initial velocities of the electrons and causing said electrons to travel along curved paths wherein the faster electrons are deflected to a smaller extent and travel longer paths in a given time than the slower electrons, and means for defining a high frequency field in the path of said electrons, said last-named means being disposed in a plane transverse to the beam path at a point past said deflecting means and so oriented that all electrons leaving the electron supplying means at the same instant of time arrive at said field defining means at substantially the same instant of time.

9. An electron discharge device according to claim 8, further including means for defining a second high frequency field in the path of said electrons, said last-named means being located beyond and inclined at an angle to said first field defining means so that all electrons of each group arrive at said second high frequency field at substantially the same instant of time.

10. An electron discharge device according to claim 9, further including cathode means for supplying a stream of electrons having random initial velocities along an electron beam path, means for deflecting said electrons inversely to the random initial velocities of the electrons and causing said electrons to travel along curved paths wherein the faster electrons are deflected to a smaller extent and travel longer paths in a given time than the slower electrons, said deflecting means comprising a pair of spaced curved plates disposed adjacent said cathode means and on opposite sides of the beam path and means connected to said plates for applying constant deflecting potentials thereto, said curved plates having a length several times the distance between the plates whereby the electrons will be deflected through a substantial angle, and means for defining a high frequency field in the path of said electrons, said last-named means being disposed in a plane transverse to said path at a point past said plates and so oriented that all electrons leaving the electron supplying means at the same instant of time arrive at said field defining means at substantially the same instant of time.

11. An electron discharge device comprising cathode means for supplying a stream of electrons having random initial velocities along an electron beam path, means for deflecting said electrons inversely to the random initial velocities of the electrons along curved paths wherein

the faster electrons are deflected to a smaller extent and travel longer paths in a given time than the slower electrons, said deflecting means comprising means adjacent said cathode means for producing a constant magnetic field transverse to the beam path, and means for defining a high frequency field in the path of said electrons, said last-named means being disposed in a plane transverse to the beam path at a point past said plates and so oriented that all electrons leaving the electron supplying means at the same instant of time arrive at said field defining means at substantially the same instant of time.

13. An electron discharge device comprising means for supplying a stream of electrons having random initial velocities along an electron beam path, means adjacent said electron supplying means for subjecting said electrons to transverse deflecting forces of constant intensity for a substantial distance to cause said electrons to travel along substantially circular curved paths, said forces deflecting said electrons inversely to the random velocities thereof whereby the faster electrons are deflected to a smaller extent and

travel longer paths in a given time than the slower electrons, and means for defining a high frequency field in the path of said electrons, said last-named means being disposed in a plane transverse to said path at a point past said deflecting means and so oriented that all electrons leaving the electron supplying means at the same instant of time arrive at said means for defining a high frequency field at substantially the same instant of time.
